UNITED STATES PATENT OFFICE

GEORGE E. RICHMOND, OF HOUSTON, TEXAS.

CONVEYER.

No. 878,671.

Specification of Letters Patent.

Patented Feb. 11, 1908.

Application filed September 1, 1906. Serial No. 332,966.

To all whom it may concern:

Be it known that I, GEORGE E. RICHMOND, a citizen of the United States, residing at Houston, in the county of Harris and 5 State of Texas, have invented a new and useful Conveyer, of which the following is a specification.

This invention relates to conveyers and is more especially designed for use in threshing 10 machines and the like, although it is equally effective when used in connection with other forms of machinery.

One of the objects of the invention is to provide a simple and durable form of conveyer which is easy to operate and which 15 will convey material in an efficient manner.

A still further object is to provide means whereby the bodily movement of the conveyer will result in the operation of means 20 for shifting material along the conveyer in the direction of its movement thereby greatly increasing the speed at which the material is moved along the conveyer without correspondingly increasing the speed of 25 the conveyer.

With these and other objects in view the invention consists of certain novel features of construction and combinations of parts which will be hereinafter more fully de- 30 scribed and pointed out in the claims.

In the accompanying drawings is shown the preferred form of the invention.

In said drawings: Figure 1 is a longitudinal section through a portion of a conveyer 35 constructed in accordance with the present invention; and Fig. 2 is a transverse section therethrough.

Referring to the figures by characters of reference, C designates the walls of a sup- 40 porting casing and secured to the inner faces of these walls are supporting rails 1 and 2 preferably in the form of angle irons suitably secured to the casing walls and having their ends downturned as shown at 3. Endless 45 chains 4 are mounted to travel upon sprock- ets 5 one of which is secured to a shaft 6 journaled in the walls 2 and one of these shafts and sprockets thereon is disposed to be located at each end of the conveyer. In the 50 drawings only one end portion of the conveyer has been illustrated as it is not deemed necessary to show all of the sprockets carrying the same. Certain of the links of the chains, preferably, the alternate ones, con- 55 stitute bearings for the transversely extending shafts 7 each of which has wheels 8 and 9

at the ends thereof. The wheel 8 on each shaft is in the form of a spur wheel and each of the rails 1 is provided with rack teeth de- 60 signed to mesh with the spur wheels so that when the chains are drawn longitudinally said spur wheels will travel upon and be rotated by the rack teeth. Arms 10 radiate from each shaft 7 and the arms of the adjoining shafts are preferably arranged inter- 65 currently so that the rotation of the shafts will not be interfered with.

Suitable guards 11 are secured to the side walls C above the upper leads of the chains so as to prevent the material which is being 70 conveyed from becoming entangled with the chains and the wheels and rails. It is ob- 75 vious that if the arms 10 were not employed straw or other similar material if placed upon the chains 4 and the shafts connecting them 80 would be conveyed thereby at a speed equal to the speed of movement of the chains. In order to facilitate the longitudinal move- 85 ment of material without however increasing the speed of the chains the radiating arms 10 have been employed. When the chains are moved longitudinally the shafts 7 are caused 90 to rotate in the manner described and the arms 10 revolve therewith and successively take up and carry the material forward in 95 relation to the chains and it will be conveyed to the arms of the next shaft and in this way the material is passed from the arms of one shaft to the arms of the adjoining shaft and moved along the conveyer at an increased 100 speed without correspondingly increasing the speed of movement of the chains. It is of course understood that the shaft 6 can be actuated by any suitable mechanism.

What is claimed is:

1. A conveyer including endless chains, 95 shafts supported for rotation in said chains, and spacing said chains apart, and support- 100 ing means for the chains; said shafts being provided with radial arms.

2. A conveyer comprising endless chains, 105 means for actuating them, arms movably mounted upon and carried by the chains, and means for actuating the arms for di- recting material longitudinally along the conveyer during the movement of said conveyer.

3. A conveyer comprising endless flexible 110 elements, means for actuating the same, revoluble series of arms carried by said ele- ments, and means for actuating said arms during the movement of the flexible ele-

ments, said arms being disposed to pass material longitudinally upon said elements during the movement of the elements.

4. A conveyer comprising endless chains, means for actuating them, shafts carried by the chains, means for rotating the shaft during the movement of the chains, and radial devices upon the shafts for directing material longitudinally along the conveyer.
- 10 5. An endless conveyer having radial de-

vices revolvably mounted thereon and movable therewith and disposed to direct material longitudinally along the conveyer.

In testimony that I claim the foregoing as my own, I have hereto affixed my signature 15 in the presence of two witnesses.

GEORGE E. RICHMOND.
